UNITED STATES PATENT OFFICE.

FRANCISCO ADOLFO LIZARRAGA, OF COROZAL, BRITISH HONDURAS.

PROJECTILE.

1,241,409.

Specification of Letters Patent. Patented Sept. 25, 1917.

Application filed December 22, 1916. Serial No. 138,522.

To all whom it may concern:

Be it known that I, FRANCISCO ADOLFO LIZARRAGA, a subject of the King of Great Britain, residing at Corozal, British Honduras, Central America, have invented certain new and useful Improvements in Projectiles, of which the following is a specification.

This invention relates to an improvement in projectiles and more particularly to bullets or other solid and non-explosive projectiles as distinguished from shrapnel or the like.

It has been demonstrated that the bullet or solid projectile as now generally in use and as provided with a more or less flat base, creates a very high vacuum in its wake, which vacuum is increased with the speed of propulsion of the bullet, thus creating a variation in atmospheric pressure and throwing up an obstacle for the range and hitting power of the projectile. It is of course to be understood that the speed of travel of the projectile will be governed in a great measure by the piece from which it is fired and that the creation of vacuum in the wake of the bullet will be somewhat dependent upon the force with which the projectile is discharged, and with the above in mind, it is a purpose of my invention to provide a bullet or other projectile of the solid type which is so formed that the projectile in its travel will part the air and the air will then sweep in at the tail of the projectile to thus cause the bullet to perforate and travel through the air without the creation of the high vacuum at the tail thereof.

A further object lies in shaping the rear end of the projectile in such a manner that it is notched to present helicoidal cuts partaking of substantially the same pitch as the rifling of the fire arm or ordnance piece from which the projectile is to be fired, the projectile being thus so shaped that as it is rotated it bores its way through the air and the air then flows down through the helicoidal cuts to destroy vacuum which would otherwise be created in the wake of the projectile.

Yet another object lies in providing structure by which the explosive charge used to impel the projectile is held against escape through the cuts at the rear end of the projectile.

With the above and other objects in view, my invention consists in certain novel fea-

tures of construction and combinations of parts which will be hereinafter set forth in connection with the drawings and then more particularly pointed out in the claims. 60

In the drawings:

Figure 1 is a view illustrating a projectile fitted in place in a shell such as might be used in a rifle or other hand fire arm.

Fig. 2 shows a perspective view of the projectile to more clearly illustrate the form of the same.

Fig. 3 is a view in elevation showing the member adapted to prevent the loss of driving force of the explosive through impact 70 with the shaped end of the projectile.

As has been stated, the device of my invention adapts itself for use as a projectile for rifles or other small arms, or for guns of larger caliber and long range, and in either 75 connection the increase in efficiency will be attained. As various uses will be made of the projectile, it will of course be understood that it may be made of the solid type, might be steel cased, soft nosed, or made of any 80 other form, and that the projectile might even be of the explosive type, and might have a brass or other soft metal ring fitted thereon to make the same follow the rifling of the fire arm in which it is to be used, and 85 therefore it is not to be understood that the form and construction as herein described is to be taken as the only shape and design which the projectile might have.

In the present instance I have illustrated 90 the projectile in the form of a bullet to be fitted in a brass or other rifle cartridge, and the projectile 1 has the outer end thereof pointed as shown at 2 to thus give greater penetrating qualities and also to lessen the 95 resistance of the bullet in passing through the air. The main body portion of the bullet is made of substantially uniform diameter throughout, and is formed to be received in the shaped outer end of the shell 3. 100 This bullet 1 can be made of the steel cased type, made throughout of a hard or soft metal, or formed and shaped in any other approved and desired manner, and at its rear end the projectile is notched and cut out 105 as is shown at 4, 5, and 6 so that the notches partake of a helicoidal form. As is here illustrated, the one side of each of the cuts as formed in the body of the projectile at the rear end thereof is disposed substantially 110 radially from the center of the projectile, and the other side is shaped to take the heli-

oidal form, although it will be apparent that some variations might be made from this exact form. It is perhaps preferable that the helicoidal form of the cuts or notches be gaged to take substantially the same pitch as is taken by the rifling of the gun barrel in which the projectile is to be used, and in this way as the projectile is fired from the barrel, the projectile will bore its way through the air and the air after passing over the body thereof will flow down over the helicoidal side of the cuts formed in the rear portion thereof and will thus rush in to relieve the tendency to the creation of a vacuum in the wake of the projectile.

The projectile might be fitted in the shaped outer end of a shell such as shown at 3, or might be fitted in at the breech of a gun to be fired by a charge of explosive placed in the gun, and also the burst of the expansion due to the explosion might be permitted to act directly upon the shaped inner end of the projectile, but it is preferable that a disk 7 made of substantially the same diameter or caliber as the projectile be provided to be fitted back of the same and to thus cover the cut and shaped inner end. When the projectile is to be used in connection with a shell, the explosive, powder, cordite, or other suitable material, is placed within the shell as is shown at 8, it of course being understood that provision is made for the firing of the shell. The disk 7 is then inserted in the shaped portion of the outer end of the shell to cover over the explosive charge, and the projectile 1 is then mounted in place, it being preferable that the shaped portion of the shell be made sufficiently long that the entire notched end of the projectile be received therein. Following the insertion of the projectile, this shaped end is rolled to obtain proper securing of the projectile and the disk, and thus the shell is completed and ready for use, the shaped portion thereof fitting snugly around the shaped inner end of the projectile acting to secure the shell against ingress of water and other foreign matter.

It will of course be understood that where the projectile is to be used in a gun of larger caliber, and without a shell, the projectile will be first placed in the breech of the gun and brought to the proper position after which the disk 7, which is preferably of glass or some other softer metal which will not injure the rifling of the barrel is mounted in place back of the projectile, following which the explosive charge is inserted. In the use of the projectile either with a shell or without the employment of a shell, the firing of the explosive charge will cause the disk 7 to be driven out and expelled from the barrel of the gun, and the projectile will be driven before this disk, the two

parts thus moving as substantially a single unit. Due to the fact that the disk 7 is of a soft material and is backed up against the rear end of the projectile with great force due to the explosion, this disk will show a tendency to follow the rifling and will aid in the initial turning of the projectile, thus perhaps relieving the necessity of placing a band or other portion to cause the projectile to follow the rifling.

70

As has been stated, it is of course apparent that the projectile might be made of various shapes and sizes to accommodate the same for the particular gun in which it is to be used but in any adaptation which may be made, the essential features to be retained are the notches in the rear end of the projectile formed to partake of a helicoidal curve, and preferably shaped to have a pitch corresponding with the pitch of the rifling of the gun. In the present disclosure I have shown only three of these notches, but it will be evident that variation can be made in the number, as well as the shape and size of these notches.

80

In the use of the projectile, as the same passes through the air, the pointed end will penetrate, and then as the air rushes in to fill the space as left vacant by the passage of the projectile at high speed, this air will pass over the sides of the body of the projectile and then down through the cuts or notches to slide off from the rear end of the projectile and thus greatly relieve the drag which is created when the air rushes over a more or less sharp rear edge on the body portion in an endeavor to fill the high vacuum space immediately in the rear of the projectile. As the projectile is under ordinary conditions being revolved as it travels forward, due to the fact that the rifling of the gun barrel has caused spinning of the bullet or other projectile, the formation of the cuts or notches to take the helicoidal shape makes the projectile of such form that the air passes readily over the curved side of the notched portion and thus the drag of the air during the passage of the projectile is greatly relieved and perhaps under some circumstances the direct drag might be almost entirely overcome, thus very materially increasing the carrying qualities of the projectile and at the same time giving greater accuracy in the use of the same due to the fact that any slight irregularity in the formation of the projectile is not felt, or permitted to act upon the projectile with the same degree of controlling force.

90

It will be apparent that the changes and variations as suggested herein, and other modifications might be made in the form and arrangement of the parts without departing from the spirit and scope of my invention, and hence I do not wish to be limited to the exact disclosure but rather only

to such points as may be set forth in the claims.

I claim:

1. A projectile having notches formed therein for passage of air in the flight of the projectile, which notches are shaped to have one of the sides thereof extend substantially parallel with the axis of the projectile and with the remaining side given a helicoidal 5 curve.

2. A projectile having the rear end thereof notched to permit passage of air, which notches have one side extended substantially parallel with the axis of the projectile and 15 the remaining sides given a helicoidal curve and tapered off into the body of the projectile.

3. A projectile of elongated form having a plurality of notches provided at the rear 20 end thereof for passage of air, which notches are spaced at equidistant points and are shaped to have one side thereof extend substantially in line with the length of the projectile, and with the remaining sides formed 25 to take a helicoidal curve.

4. A projectile of elongated form adapted for use in conjunction with a gun having the barrel thereof rifled, which projectile has notches formed therein with one side of each 30 notch extending substantially parallel with the axis of the projectile and the remaining side of each notch shaped in a helicoidal curve to conform substantially to the line of twist as given to the projectile by the rifling 35 of the gun barrel.

5. A projectile of elongated form having the rear end thereof provided with a plurality of notches which are spaced at equidistant points, said notches each having one of the 40 sides thereof substantially radially disposed and extending in line with the axis of the projectile and with the remaining side

formed in a helicoidal curve, and said notches being extended into the body of the projectile to substantially the center thereof 45 at the rear end and merging into the body of the projectile at their forward ends.

6. A projectile having the rear end thereof notched to permit passage of air rearwardly on and within the outline of the 50 same during flight, and a disk shaped to be fitted against the rear end of the projectile to receive impelling force and to bear against and move the projectile.

7. A projectile having the rear end thereof notched on the side to take a helicoidal curve, and a disk shaped to be fitted against the rear end of the projectile to receive impelling force and to bear against and move 55 the projectile.

8. A projectile of elongated form having the rear end thereof notched at the side to present one side of the notch to extend substantially radially from the center of the projectile and with the remaining sides 65 formed in a helicoidal curve, and a disk shaped to be fitted against the rear end of the projectile to receive impelling force and to bear against and move the projectile.

9. A projectile of elongated form adapted 70 for use in conjunction with the gun having the barrel thereof rifled, said projectile having the body portion thereof notched to partake of a helicoidal curve to follow the pitch of the rifling of the barrel, and a disk shaped 75 to be fitted against the rear end of the projectile to receive impelling force and to bear against and move the projectile.

In testimony whereof I affix my signature in presence of two witnesses.
